UNITED STATES PATENT OFFICE.

EUGÈNE J. REMILLON, OF MOBERLY, MISSOURI.

THREE-THROW SWITCH.

SPECIFICATION forming part of Letters Patent No. 352,426, dated November 9, 1886.

Application filed June 1, 1886. Serial No. 203,811. (No model.)

To all whom it may concern:

Be it known that I, EUGÈNE J. REMILLON, of Moberly, in the county of Randolph and State of Missouri, have invented a certain new and useful Improvement in Three - Throw Switches, of which the following is a full, clear, and exact description, reference being had to the accompanying drawing, forming part of this specification, and which is a plan 10 of a three-throw switch illustrating my invention.

My invention relates to the construction of a three-throw switch; and it consists in features of novelty, hereinafter fully described, 15 and pointed out in the claims.

A A' are the main rails. A'' A''' are extensions thereof.

B C are point-rails arranged on the inside of the rails A A', having their points held 20 against their respective rails.

B' C' are point-rails arranged on the inside of the point-rails B C, having their points held away from their respective point-rails. The point-rails B B' and C C' are connected to 25 gether in such a manner that when the point-rails B C are held against their respective main rails the point-rails B' C' are held away from their respective point-rails. When either the point-rail B or the point-rail C is shifted in 30 ward, the innermost point-rails are in close contact with both of them. At the portions of the point-rails B C which are adjacent to the extreme ends of the point-rails B' C' are brackets E, to which are pivoted the outer 35 ends of crossed rods D, whose inner ends are pivoted to brackets E' on the web portions of said extreme ends of the point-rails B' C'.

F are the pivot-pins by which the rods are hinged to the brackets. The outer portions, 40 B'' B''', of the point-rails B B', and the outer portions, C'' C''', of the point-rails C C', are connected by parallel rods D', brackets E'', and pivot-pins F'.

It will be seen that the rods are connected to their respective points and cross each other 45 in front of the end of the opposite rail to which it is secured. The only secure manner of fastening between the rods and rails is to connect the rods to the webs of the rails, which is accomplished by crossing them in front of the 50 rails, as shown, a secure fastening being thus obtained between the rods and the rail-points, and that without any bending or shaping of the rods.

Having thus described my invention, the 55 following is what I claim as new and desire to secure by Letters Patent:

1. In a three-throw switch, the combination of the outer point-rails, B C, inner point-rails, B' C', and the crossed rods D in front of the 60 inner point-rails, secured to the webs of the outer point-rails and to the webs of the extreme ends of the inner point rails, substantially as described.

2. In a three throw switch, the combination 65 of the outer point-rails, B C, inner point-rails, B' C', brackets E, secured to the webs of the outer point-rails, brackets E', secured to the webs of the extreme ends of the inner point-rails, pivots F F', and the crossed rods D in 70 front of the inner point-rails secured by said pivots to the brackets.

3. A three throw switch consisting of the main rails A A', having extensions A'' A''', point-rails B B' C C', having outer portions, 75 B'' B'''' C'' C''', crossed rods D, brackets E E', and pivots F, connecting the extreme ends of the innermost point-rails to the outer point-rails, and the parallel rods D', brackets E'', and pivots F', connecting the outer portions 80 of the point-rails, substantially as shown and described.

EUGÈNE J. REMILLON.

In presence of—

JOHN W. NUTE,
M. H. SOURS.
